CLAIM

The ornamental design for a corner protector as shown and
described.

DESCRIPTION

FIG. 1 is a top front perspective view of a first embodiment
of a corner protector showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is top rear perspective view of FIG. 1;

FIG. 9 is a perspective view of the first embodiment of the
corner protector in an environment of use.

FIG. 10 is a top front perspective view of a second embodiment
of a corner protector showing my new design;

FIG. 11 is a front view of FIG. 10;

FIG. 12 is a rear view of FIG. 10;

FIG. 13 is a left side view of FIG. 10;

FIG. 14 is a right side view of FIG. 10;

FIG. 15 is a top view of FIG. 10;

FIG. 16 is a bottom view of FIG. 10; and,

FIG. 17 is a perspective view of the second embodiment of
the corner protector in an environment of use.

The dash-dash broken lines depict environmental structure
that forms no part of the claimed design. The dot-dash lines
in the drawings are represent the boundary of the claimed
portion and the unclaimed portion and form no part of the
claimed design.

1 Claim, 10 Drawing Sheets
